C. P. WATSON

PERCUSSION FUSE

Filed Aug. 27, 1923

By John S. Parker

Attorney

Inventor,

Charles P. Watson

UNITED STATES PATENT OFFICE.

CHARLES P. WATSON, OF YORK, PENNSYLVANIA.

PERCUSSION FUSE.

Application filed August 27, 1923. Serial No. 659,623.

To all whom it may concern:

Be it known that I, CHARLES P. WATSON, a citizen of the United States, residing at York, in the county of York and State of

5 Pennsylvania, have invented certain new and useful Improvements in Percussion Fuses, of which the following is a specification.

10 My invention relates to percussion fuses such as are used in connection with ordnance projectiles, some of the novel features of which, however, are adapted for use in fuses used for other purposes.

15 In my pending application for U. S. patent, Serial No. 502,385, filed September 22, 1921, I have illustrated a percussion fuse having many features in common with that which I illustrate and shall herein describe. Some of the features of novelty that may be 20 illustrated in this case, and which are also illustrated in my aforesaid application, are claimed in the latter.

Referring to the accompanying drawings—

25 Figure 1 is a central longitudinal section of a percussion detonating fuse adapted to be applied to a high explosive shell embodying my present improvements, the parts of the fuse being in safety or unarmed position.

Figure 2 is a central longitudinal section of the fuse, the parts being in armed position.

Fig. 3 is a transverse sectional view taken 35 on the line III—III of Fig. 1.

Fig. 4 is a detail face view of the plug that carries the primer.

Fig. 5 is a detail face view of the metal disk that is located between the carrier for 40 the primer and the carrier for the detonator, and the felt cover therefor.

Fig. 6 is a view similar to Fig. 5 with the primer plug also represented.

Fig. 7 is a central longitudinal sectional 45 view through a primer plug of different form from that illustrated in Figs. 1 and 2, and the carrier for the detonator and the immediately associated parts.

Fig. 8 is a central longitudinal sectional 50 view of a disk carrying two primers arranged in tandem.

Fig. 9 is a central longitudinal section similar to Fig. 7 but showing still another embodiment of my invention.

55 Fig. 10 is a cross sectional view taken on the line X—X of Fig. 9.

Fig. 11 is a central longitudinal sectional view of the carrier for the detonator unloaded, and drawn to a larger scale than the other views.

The detonating fuse represented in the drawings is of the base type adapted to be screwed into the rear of a projectile and has a body 2, in the forward end of which is formed a chamber 8 for the booster charge and in the rear portion a second chamber, 33, in which are located the several functioning mechanical elements of the fuse. The two chambers are connected by a channel of communication, 34, formed 60 through the partition separating the chambers, which passage serves as a channel of detonation between the detonator 41 and the booster charge. The chamber 33 is open 65 toward the rear but is adapted to be closed by a screw-threaded plug 6, formed with a flange 7 adapted to abut against the end of the stock or body 2 of the fuse.

70 Within the chamber 33 is located the movable hammer block 5 that carries the firing pin 13. This hammer block is preferably formed of a cylindrical piece of metal that fits the chamber 33 fairly closely, and is of a length less than that of the chamber so that it is free to move longitudinally therein as the fuse functions. Between the rear end of the hammer block and the closing plug 6, and seated in recesses, 45 and 46, formed therefor, respectively, in the plug and hammer block, is a coil spring 75 80 the opposite ends of which are respectively connected with the said parts. These connections are conveniently formed by internally screw-threading the apertures 45 and 46, as indicated at 47, and causing the coils 85 of the spring 3 to engage with said threads, by a screwing action. The spring is contractile in its tendency and serves to hold the plunger or hammer block, preventing forward creeping thereof during flight of 90 the projectile. It will be understood that the spring is not strong enough to offer any substantial opposition to the forward movement of the hammer block when the projectile strikes the target, and when this occurs 95 100 the block will move forward, carrying the firing pin into functioning engagement with the primer of the fuse, causing the firing of the latter.

110 In the forward portion of the hammer block is formed a slot 10 in which lies the firing pin 13, which is supported upon a

transverse pivot pin 12 in such manner as to be free to oscillate thereupon. The firing pin has connected with it, either integrally or as a separate piece, an eccentrically disposed part 16 that is adapted, when acted upon by centrifugal force, developed by the rotation of the shell in flight, to move the firing pin to the armed position represented in Fig. 2, the pin then 10 extending beyond the front face of the hammer block. When the fuse is unarmed, the firing pin being turned to the position represented in Fig. 1, its point is then entirely within the slot or recess 10 and therefore 15 so shielded that it cannot under any conditions act upon the primer of the fuse. Seated in an eccentric aperture 11 in the hammer block is a pin or freely moving plunger 24 acted upon by a spring 25 that 20 tends to move it inwardly. The end of this pin is adapted to enter a recess 4 formed in the eccentric portion 16 of the firing pin and thus hold the latter locked in unarmed position. A removable sleeve 25 25 surrounds the forward portion of the hammer block and serves to maintain the pivot pin 12, the plunger 24 and the spring 25 that acts on the latter, in place, this sleeve being slipped over the hammer block 30 after the parts just referred to have been properly assembled. A second plunger pin 38 is supported in an aperture provided therefor in the hammer block parallel to the longitudinal axis thereof and is acted 35 upon by a spring 39 that tends to move it in a forward direction. This pin, 38, bears against a face, 14, of the eccentric 16, when the firing pin occupies the safety position represented in Fig. 1, and acts to 40 maintain the firing pin in this position against any tendency that might tend to move it into armed position, such as centrifugal force generated by the rotation of a shell carrying the fuse if it should for 45 instance roll down an incline. The pin maintains this locking position until moved rearward against the action of its spring 39, as for instance when the plunger is violently "set back" at the instant of firing 50 the projectile carrying the fuse from a gun. The two plunger pins 24 and 38, movable on lines which are at right angles to each other, and one adapted to be "set back" against the action of its spring when the 55 shell is fired, and the other to be "set back" by centrifugal force while the shell is in flight, serve to maintain the firing pin in safety position under all conditions to which the fuse may be subjected except 60 those which are incident to the firing of a shell carrying the fuse from a gun. When this takes place the pin 38 "sets back", as has been stated, freeing the firing pin so far as any restraint from the pin 38 is 65 concerned. The plunger pin 38 is main-

tained in its "set back" position while the shell is accelerated in flight, that is, until it reaches a position some distance in advance of the muzzle of the gun. The disposition of the eccentric weighted part 16 70 of the firing pin is such that it is subjected not only to the action of centrifugal force generated by the rotation of the fuse, but also to the force of inertia, upon the shell being started in its forward movement from the gun, which latter force tends to maintain the part 16 and the firing pin connected therewith in the safety position represented in Fig. 1, until acceleration of the shell ceases, because this force of inertia 75 is more powerful during the period of violent acceleration than the centrifugal, and hence overcomes the latter. As soon, however, as the shell begins to rotate and centrifugal force is developed, the locking 80 plunger pin 24 is moved to free the firing pin, which is turned into armed position as soon as the centrifugal force acting on part 16 becomes effective, as against the force of inertia acting thereon as just set 85 forth, and this takes place shortly after the shell has left the muzzle of the gun. This feature is very important as it insures that the plunger is not armed while the fuse and loaded shell are in the bore 90 of the gun. Premature explosions in the bore of the gun cannot therefore take place, due to any obstruction in the rifling, to which such premature explosions have been attributed. 100

Locking pin 38 has a little play in the aperture in which it is located, so that when the shell is in rotation it tends to hug the outer wall of its recess, due to the action of centrifugal force, and the recess for this pin is so located that its outer edge lies a little outside of the inner edge of the sleeve 9. The result of this arrangement is that as soon as acceleration of the shell in its flight ceases, shortly after passing the muzzle of the gun, the spring 39 acts to advance the plunger or locking pin 38, but moves it only far enough to cause the end of the plunger to come into engagement with the edge of the sleeve 9, 105 where it is held in a position that will not allow it to interfere with free movements of the firing pin. The engagement of the pin 38 with the edge of the sleeve is very slight, but is sufficient for the purpose stated, especially when held in such engagement by centrifugal force. At the instant the shell strikes armor plate or other target, the resistance offered by the slight engagement of the pin 38 with the edge of 110 the sleeve is overcome and the pin moves forward to its fullest extent and lies outside of a face 15 of the eccentric portion of the firing pin, in which position it 115 operates to positively hold the pin so that it 120

cannot possibly tilt or move as the pin comes into engagement with the primer of the fuse when the hammer block moves forward. This feature insures a rigid firing

5 pin when the latter strikes the primer and provides for certainty of firing the primer, by transmitting the maximum blow to its center and most sensitive part.

The forward portion of the recess 33 is 10 internally screw-threaded, as represented at 17, to receive a plug 18, that carries the primer 19. This plug is formed with an axial opening 40 through which the firing pin acts, and has cut in its front face a series 15 of flash passages 20 leading from the primer seat to the periphery of the plug.

To insure greater certainty of primer action on graze or slight impact it is proposed to use two primers in tandem, as represented 20 in Fig. 8, the first or rear one, 19', to be a shallow stab type primer, and the second, 19", of the ordinary percussion type—both being made as sensitive as practicable; or, 25 under certain conditions, two stab type primers may be used in tandem.

In advance of the primer plug is located another plug, 21, carrying the detonator 41

and a powder pellet or train 42 that serves as the time or delay element of the fuse.

30 The detonator plug 21 is preferably formed from a block of metal cylindrical in shape and of a size to fit as closely as possible the cylindrical recess 33, and yet allow it to be inserted in its place next to the partition

35 that separates the two chambers 8 and 33 of the fuse, where it is securely held by the primer plug 18 when that is screwed into place.

40 The detonator 41 is located in a cavity 27 formed in the forward portion of the detonator plug 21. The detonator may be of fulminate of mercury, fulminate of mercury with an oxidizing agent, lead nitrid, or other detonating substance. It may also be made of fulminate of mercury or 45 other detonating substance with a high explosive like tetryl or trinitrotoluene, either blended or in layers.

The cavity 27 is of such shape that its walls, which are thick and rigid, will reflect and direct forwardly the waves of detonation incident to the explosion of the detonator 41. While I prefer that the shape of the cavity shall be parabolic, that is not the only shape which will give good results.

55 For instance, the rear end only of the cavity may have its walls shaped to reflect and direct forwardly the detonating waves. On the other hand, the entire wall surface of the

60 cavity may be shaped to act to reflect and direct the detonating waves; and, since parabolic and ellipsoidal shapes for the wall surface give the last-mentioned results, that is, insure utilization of the entire surface of the cavity for reflecting purposes, these latter shapes give the best results; but, as

stated, good results are obtained when the rear end only of the cavity is rounded or made flaring outwardly, while the forward portions of the wall are cylindrical.

The cavity 27 is practically closed at its 70 rear end, that is, it is closed so far as it serves as a reflecting surface for the waves of detonation. In the form of invention shown, which is designed for a detonating fuse, there is the small ignition hole 28, forming 75 part of the channel of ignition leading into the cavity 27, but this is of so small area as to be practically negligible so far as interfering with the reflecting properties of the cavity wall is concerned.

The method of directing and concentrating detonating waves in its more general applications is fully explained and claimed in applications which I have already on file

20 in the Patent Office of the United States, one of which applications, #502,385, has already been specifically herein referred to;

25 and it is, therefore, unnecessary for me to here explain the theory by which such waves of detonation are reflected, directed

30 and concentrated so they become increasingly effective.

In order to obviate a premature discharge of the detonator on the shock of discharge

35 of the gun firing the shell containing the fuse, and to a greater extent on the shock of impact of the said shell on hard and

40 cylindrical recess 33, and yet allow it to be inserted in its place next to the partition cavity under very high compression, e.g.—

45 that separates the two chambers 8 and 33 of the fuse, where it is securely held by the primer plug 18 when that is screwed into place.

50 The detonator 41 is located in a cavity 27 formed in the forward portion of the detonator plug 21. The detonator may be of fulminate of mercury, fulminate of mercury with an oxidizing agent, lead nitrid, or other detonating substance. It may also be made of fulminate of mercury or other detonating substance with a high explosive like tetryl or trinitrotoluene, either blended or in layers.

The cavity 27 is of such shape that its walls, which are thick and rigid, will reflect and direct forwardly the waves of detonation incident to the explosion of the detonator 41. While I prefer that the shape of the cavity shall be parabolic, that is not the only shape which will give good results.

55 For instance, the rear end only of the cavity may have its walls shaped to reflect and direct forwardly the detonating waves. On the other hand, the entire wall surface of the

60 cavity may be shaped to act to reflect and direct the detonating waves; and, since parabolic and ellipsoidal shapes for the wall surface give the last-mentioned results, that is, insure utilization of the entire surface of the cavity for reflecting purposes, these latter shapes give the best results; but, as

65 stated, good results are obtained when the rear end only of the cavity is rounded or made flaring outwardly, while the forward portions of the wall are cylindrical.

The cavity 27 is practically closed at its 70 rear end, that is, it is closed so far as it serves as a reflecting surface for the waves of detonation. In the form of invention shown, which is designed for a detonating fuse, there is the small ignition hole 28, forming 75 part of the channel of ignition leading into the cavity 27, but this is of so small area as to be practically negligible so far as interfering with the reflecting properties of the cavity wall is concerned.

The method of directing and concentrating detonating waves in its more general applications is fully explained and claimed in applications which I have already on file

20 in the Patent Office of the United States, one of which applications, #502,385, has already been specifically herein referred to;

25 and it is, therefore, unnecessary for me to here explain the theory by which such waves of detonation are reflected, directed

30 and concentrated so they become increasingly effective.

there is an igniting passage 28 communicating with the cavity 27 for the detonator. A central axial opening 38, much larger in diameter than the igniting passage 28 and 5 preferably co-axial therewith, is formed in the hub portion 49 of the plug 21, leading from the rear face of the latter to the diametric hole 23. Into this larger axial opening is inserted a tightly fitting plug or closing piece 26, the wall of the opening being preferably screw-threaded to receive such plug. A delay powder train 42 is located 10 in the hole or transverse passage 23. The passage preferably opens at each end into the space 22, so that the powder train 42 is 15 ignited from each end and thus in effect becomes two trains which approach each other at the axial center of the detonator plug. These trains consist each of a mass of compressed black or other relatively slow burning 20 powder that fills the hole 23 from one open end thereof to about where the closing plug 26 is seated. The central portion of the hole 23 is filled with and constitutes a 25 magazine for a small charge of loose fine grain igniting powder, 42^a. This magazine may be conveniently loaded through the central axial opening, after which the closing plug 26 is applied. The inner walls of the 30 hole 23 are preferably screw-threaded, and the powder train, being compressed therein, fills the grooves between the threads, and thus there is formed an easy and convenient means for effectively preventing flame or 35 hot gases from creeping along the outside of the delay train in advance of the complete burning thereof, as has been found to sometimes occur when the powder train is loaded into a small passage having smooth 40 walls.

A thin disk or plate 31, preferably of metal, lies between the primer plug 18 and the detonator plug 21, the diameter of this disk being practically the same as that of 45 the plug 21. Its edge is notched, as indicated at 35, and to one of its faces is secured a washer 32 of felt or similar yielding material. In assembling the parts of the fuse the washer 32 is placed next the inner 50 end of the hub of the plug 21. It serves the double purpose of a cushion between the screw or primer plug and the detonator plug, and also as a seal against the passage of flame from the igniting passage 22 to the 55 axial opening into which is set the plug 26. While the latter plug is intended to make the axial opening gas tight, it is possible that under the great strains that obtain upon impact of a shell the flame from the primer 60 might reach the magazine of igniting powder, 42^a, through the axial opening in the hub 49, and thus cause firing of the detonator without reference to the action of the delay train.

65 The use of the two powder time trains not

only provides greater certainty in the ignition than if one only were used—but when both are ignited simultaneously and burn toward each other the resulting subsequent ignition effect is greatly increased when 70 both burn out at the same instant. In such case the magazine of loose igniting powder may be dispensed with. It is practicable to use one, or more powder trains,—and the greater the number the more certain the ignition thereof, and the greater the resulting igniting effect under favorable conditions. 75

The number of notches 35 in the edge of the disk 31 differs from the number of igniting passages 20 and these two are respectively so arranged that the parts 18 and 31 cannot be properly assembled without one or more of the flash passages communicating with one or more of the notches 35, with the result that there is always a communication 80 between the primer recess and the peripheral flash passage 22, so that when the primer is fired the flame therefrom is communicated to the opposite ends of the delay train, but through tortuous passages; which is of advantage, as better results are obtained in igniting a delay powder train if the intense blast of flame from the primer is not communicated directly to the end of the powder train to be ignited, but rather in an indirect 85 manner, as through a tortuous passage such as described. By having two delay trains with two ends therefore that may be ignited, I reduce the danger of failure to fire the magazine of igniting powder. Each compressed powder train is formed to give the delay, say one-tenth of a second, that is desired in the functioning of the fuse upon impact. 90

95 36 designates a shield or protecting cap 105 covering a portion of the forward end of the plug for the detonator, which end is preferably curved or dome-shaped to fit the face of the partition wall 44 that is toward the cavity 33. This shield is preferably 110 formed of thin metal and serves to maintain the detonator in its cavity 27 and protect it against the set forward on impact of the shell. The shield is crimped at its circumference into a corresponding groove cut in 115 the detonator plug so that it acts as a gas check. Under said shield 36 is preferably placed a disk 51 of water-proof paper.

Under certain conditions it may be found necessary to make the metal shield thicker 120 at the middle than the edge, and of lens shape so that it serves to refract the detonating waves arising from the explosion of the detonator.

125 In Fig. 7 I illustrate another and somewhat more simple form of plug for the detonator delay train of the fuse. In this form of the invention the delay train or pellet is located in an open recess 23' formed in the rear face of the cylindrical piece 21,— 130

instead of in a passage like that designated 23, closed except at its ends. The open cavity 23' is covered and closed by the felt washer 32 carried by the plate 31. It is 5 connected at one end with the base of the detonator cavity 27, by an igniting passage 50, and at the other end with the circumferential flash or igniting passage 22. This latter form of carrier plug for the detonator and delay train is easier to make than 10 those shown in other designs and has the advantage of giving a more uniform time of burning, though the possibility of short-circuiting is greater, when the assembling 15 is not properly done. I have shown this particular design in duplicate to insure the ignition of the delay feature of the fuse.

It is also practicable, as represented in 20 Figs. 9 and 10 to dispense entirely with the central axial opening with its closing plug 26 and yet retain the advantages incident to that construction. In this case an off-center hole 60 is drilled through the hub 49 of the plug, the axial center of which is 25 a chord through the hub. Another hole 61 passes through the smaller segment of the hub produced by the hole 60, and communicates at right angles with the hole 60 at its center. The hole 60 communicates with the 30 igniting passage 28 through a small passage 62.

In using this form of the invention the hole 60 is loaded from end to end with black or other slow burning powder compressed 35 to a considerable degree. A proper tool is then passed through the hole 61 and cuts out the central portion of the powder train in hole 60, forming two delay powder trains whose exposed ends are respectively at the 40 opposite sides of the hub 49. A loose charge of fine grain black powder to constitute the magazine of igniting powder is then introduced into the space between the ends of the compressed delay powder trains in the hole 45 60, and is there confined by a plug 63 which is tightly fitted into the hole 61.

There a number of practical advantages 50 incident to carrying both the detonator and the delay or time trains, including the magazine of igniting powder, in a single part separable from the body of the fuse, and adapted to be easily placed therein in proper 55 relationship to the primer and the booster. The detonating plug 21 is simple in construction and easily and cheaply manufactured. It may be easily loaded, and, when 60 loaded, constitutes a complete article that is furnished to those who assemble and load the fuse. This makes for safety as well as cheapness in manufacture. The steel and notched disk and the detonator plug heretofore described pertain to a delay detonating fuse. By omitting the disk, perforating the center of the felt washer, and also

omitting the closing plug, the fuse can be 65 converted into a normal quick acting fuse.

Through the heavy wall 44 separating the two main chambers of the fuse is formed the channel of detonation between such chambers. The portion of the channel of detonation entering the chamber for the booster charge is covered by a shield 56 of thin metal, cup-shaped to conform to the channel and the bottom of the chamber. Its 70 object is to prevent any of the explosive 75 from the booster charge entering the passage in which the oscillating bolt operates. Any other suitable retaining device can be employed. For certain booster charges or 80 certain kinds of loading the shield or retaining device may be dispensed with. Intercepting this channel is an oscillating bolt or 85 turret 29 through which is a diametric passage 30 that, when brought into alignment with the two parts of the channel of detonation formed in the wall 44, registers therewith and constitutes part of such channel. The means for automatically operating the bolt 29 are fully illustrated and described in my aforesaid application #502,385, 90 and need not be specifically described herein. Suffice it to say that the bolt under normal safety conditions is turned to such position that the diametric passage through it 95 does not register with the channel of detonation, but instead the bolt acts to intercept this channel and constitutes a barrier between the chambers 33 and 8, so that should any or all of the explosive elements located 100 in the chamber 33 prematurely or accidentally ignite the forces generated thereby would be effectively cut off from the booster charge and would not ignite the latter. When, however, the shell is fired from a gun the 105 oscillating bolt is automatically operated and moved from its safety position, intercepting the channel of detonation, and turned so as to bring the diametric passage through it into register with the stationary 110 parts of the channel of detonation.

There is also provided within the fuse stock and between the chamber for the booster charge and that for the firing mechanism, etc., an expansion chamber 52. Should there be any explosion of the detonator when 115 the oscillating bolt is in its safety position the effect would be to cause a flattening out of the oscillating bolt and the escape of the gases from the explosion into the expansion chamber.

As in case of the hammer block or firing plunger, the oscillating bolt does not move into the armed position until after the shell has left the bore of the gun. A premature explosion of the detonator in firing would not, therefore, lead to a detonation of the shell and resulting destruction of the gun.

The oscillating bolt is assembled to the

fuse from the exterior and there is a chamber or opening 54 in the side of the fuse stock for the purpose. There is also provided in the side of the fuse a screw hole 55 leading to the expansion chamber 52 and closed by a screw-threaded plug 53. After the oscillating bolt has been assembled to the fuse, or at any time thereafter, it is practical to unscrew the plug 53 and ascertain whether or not the oscillating bolt is in its desired safety position, since the hole 55 is so located as to be directly opposite the end of the diametric opening through the oscillating bolt when the latter is in safety position.

The detonating fuse herein described and illustrated possesses the very desirable features of being readily loaded and assembled from the exterior and practically in the order of danger of the various component elements. In this design it is practical and desirable, to assemble, as the first operation and from the exterior, the oscillating barrier bolt, thus intercepting the channel of detonation. The second operation is to load, from the front end and exterior, the booster charge. The third operation is to assemble the detonator, primer, and firing mechanism elements, from the rear end and also exterior. When such a fuse is assembled with only the oscillating bolt and booster charge, it can be readily transported as a safety explosive, the remaining elements to be assembled at the place where the fuse is required to be used in the loading of shell.

In assembling the fuse it is the practice, and makes for safety, to remove the plug 53 and inspect the barrier bolt to insure that it is in safety position before the third operation of assembly is performed; and such an inspection, likewise, insures that during handling and transportation the fuse cannot be detonated.

A fuse such as that described functions as follows: Upon a shell carrying the fuse being fired from a gun the locking plunger pin 38 sets back and frees the firing pin. This, however, remains in safety position so long as the shell is under acceleration, as has been pointed out. In the meantime centrifugal force causes the locking plunger pin 24 to move outwardly, freeing the firing pin from its restraining influence, so that as soon as the shell has left the muzzle of the gun and acceleration in its flight has ceased, the firing pin will turn on its pivot and become armed, as has been described. The oscillating bolt also remains in safety position until after the shell has left the gun, when it also is armed, as has been described. During the flight of the shell the centrifugal force maintains the firing pin in its armed position. Upon impact of the shell against the target the locking bolt 38 moves forward

into position to positively maintain the firing pin in armed position, as has been described. At the same instant, the hammer block springs forward, against the action of the anti-creeping spring 3, and the firing pin acts upon the primer, firing it. The flame from the primer passes through the flash or igniting passages 20, through one or more of the notches 35 in the disk 31, and into the circumferential flash or igniting passage 22, which becomes filled with flame and ignites the powder train. These burn progressively until their inner ends are reached, when the flame therefrom, reinforced by that from the magazine of igniting powder, passes through the flash passage 28 and ignites the detonator. The waves of detonating force generated by the explosion of the detonator being reflected and directed forwardly by the reflecting walls of the cavity 27 ruptures the shield 36 and pass through the open channel of detonation across a considerable air gap or gaps into the booster charge, firing the latter. The rigid reflecting walls of the booster chamber reflect and direct the waves of detonating force, produced by the detonation of the booster charge, forwardly into the mass of explosive constituting the bursting chamber of the shell which is thereby detonated.

The capacity of the detonator in this fuse to detonate the booster charge across a considerable air gap constituting the open channel of detonation is its most striking feature. In this particular design the length of the air gap is approximately five times its diameter, and the detonation across such a gap represents an accomplishment not heretofore obtained in the art. The set forward of the shell charge on impact may give rise to a considerable air gap in the rear of the cavity of the shell, and between the fuse and the bursting charge. The fuse is designed so that the detonating waves from the explosive of the booster charge will jump this air gap and detonate the bursting charge.

In this specification and the subsequent claims, the term "primer" refers to the initiator of the explosion of the fuse and may be the ordinary percussion type of primer, the stab type of primer, or, in case of fuses for bombs or other containers for high explosive, any igniting type of primer. The term "detonator" refers to the usual detonating charge which initiates the detonation or explosion of the fuse, and is ordinarily of fulminate of mercury, although it may be of other detonating substances used in a similar capacity. The term "detonating explosive" as used, applies not only to the detonator as herein described, but also to what is commonly known as the booster charge used to detonate larger charges of high explosive. The term "high explosive" covers such high

explosive substances as may be used in a detonator, in a booster charge, or in a shell, bomb, or other container.

Throughout this specification the term 5 "waves of detonation" has been employed. As understood by writers on the subject of explosives "waves of detonation" refer specifically to the waves that are propagated throughout the mass of a high explosive as 10 it is being detonated or very violently exploded. The velocities of these waves of detonation have been determined for various explosives and they are very high. But, in this specification the term "waves of detonation" 15 not only applies to the waves of energy that are propagated through the mass of detonating explosive, but also to the waves of force which my invention has demonstrated act exterior to and beyond the mass of explosive detonated. In the latter case, these 20 waves of force have extraordinary detonating capacity, so much so that they will detonate another high explosive over an air gap the length of which is at least five times its 25 diameter.

I have demonstrated that these waves of detonating force arising from the detonation of a booster charge having an extreme diameter of one inch will effectively detonate the 30 bursting charge of a shell over an air gap of six inches. This air gap is not enclosed, except in so far as the interior wall of the shell may enclose it, and, therefore, in this respect is unlike the enclosed channel of detonating 35 force between the detonator and the booster charge of the fuse herein described.

In regard to the character of the waves of detonating force which act exterior to the mass of explosive the detonation of which 40 gives rise to them, I find, by reference to Berthelot's Work on Explosives and Their Power, edition of 1892, that this distinguished French authority on explosives has recognized two kinds or orders of detonating 45 waves. In explaining these detonating waves Berthelot on pages 79 and 80 of his work, used the following language:

"Such is the theory which appears to the author to account for explosions by influence, and for the phenomena which accompanied them.

"It rests on the production of two orders of waves; the one being the explosive wave, properly so called, developed in the substance which explodes, and consisting of a transformation incessantly reproduced from chemical actions into calorific and mechanical actions, which transmit the shock to the supports and contiguous bodies; and the other purely physical and mechanical, which also transmits sudden pressures around the center of vibration to neighboring bodies and by a peculiar circumstance to a fresh mass of explosive matter."

65 The first order or kind of detonating wave

is that which is propagated through the mass of explosive as it is being detonated, and is the result of chemical action throughout the explosive. The second order or kind, referred to as a purely physical and mechanical detonating wave, constitutes the "influence" or waves of influence which detonate across air gaps or at a distance.

The presence of these waves of influence has been recognized by other writers on explosives, as Marshall and Brunswig; and whenever one explosive is detonated which is not in contact with the explosive initiating its detonation, the phenomenon is attributed to influence.

Heretofore all detonating fuses have had the several explosive bodies or agencies in close contact with each other at the time of detonation, and the train or channel of detonation, where there was one, has always been a channel filled with explosive, so that the train from the detonator to the booster charge and to the bursting charge of the shell has been one of contact of high explosive substances. But I employ for detonation transmission an open channel of detonation of considerable length, and across the air gap thus formed and through this open channel of detonation I am able to successfully detonate the booster charge. Undoubtedly this detonation has been accomplished by "influence," or waves of influence, or the physical and mechanical waves referred to by Berthelot, and which are referred to in the specification and accompanying claims as "waves of detonating force." These waves of influence have been measured by scientists, and it has been noted that their intensity and velocity fall off from the center or focus of the detonation which gives rise to them, whereas, the first order or kind of detonating waves are all of practically constant velocity and intensity throughout the mass of the explosive.

While these waves of influence may fall off in intensity and velocity as stated above under ordinary conditions, I have, however, by means described, been able to reflect, direct and concentrate them, and have thus given them greater detonating power than if they were not so controlled, thus more than compensating for the normal falling off in their intensity due to distance from their source.

In the early experiments conducted by the Engineer Corps of the Army it was found that the detonation of one submarine torpedo would within a certain radius give rise to the detonation of another submarine torpedo; and it was also found that this influence or these waves of influence will act at a greater distance in a fluid medium like water, than they will in air.

The phenomenon of detonating the booster charge by the reflecting and directing of the waves of influence from the detonator as

stated in this specification has also been observed in case of the detonation of the booster charge, for in the latter case the waves of influence will act across a considerable air gap and successfully detonate the bursting charge of the shell.

Ordinarily air is the fluid that fills the open channel of detonation, and by open channel in the specification and the claims is meant a channel free from explosive. I do not wish, however, that my invention be limited to the use of air as the only fluid medium for transmitting this second order of waves of detonation, or waves of influence, because it is conceivable that other fluids, gaseous and liquid, can be used advantageously.

Throughout the specification and claims where I have employed the words "waves of detonating force" I have used them synonymously with "influence," waves of influence, or the physical and mechanical waves referred to by Berthelot. And the discussion in this specification will make it obvious that these waves of influence are quite different from the ordinary or chemical, waves of detonation which depend upon contact or intimate association of the explosive elements for their propagation and utilization in detonating fuses. But in case of the detonating fuse herein described, I have utilized "influence" or waves of influence, in the successful detonation of the fuse and shell which has not heretofore been accomplished, and marks, therefore, a great advance in the art. The operation of the fuse is therefore different from any other in use.

The phenomenon arising from the experimental work conducted by me in the development of the detonating fuse herein described is obviously quite different from any phenomenon exhibited by the behavior of other detonating fuses of which I have any knowledge, for I have been able to secure remarkable results with a detonator the mass of which is about one-fifth of that used in other detonating fuses, while the mass of the booster charge is not over one-third of the mass of those generally used in other detonating fuses for similar work.

Many of the features described are applicable to fuses for bombs, torpedoes and other containers of high explosives.

By my invention I secure—

55 First. A fuse so designed that it is safe in handling and storage against shock and rough usage;

Second. A fuse so designed that when assembled in a shell loaded with high explosive, there cannot be detonation of such shell in storage, handling, or during its flight in the bore of a gun, from any cause peculiar to the fuse;

Third. A fuse so designed that it operates

satisfactorily even when the detonator is loaded under a very high degree of compression;

Fourth. A fuse so designed that it requires much less of a detonator and of a booster charge than has been heretofore employed in the art;

Fifth. A fuse so designed that the detonator detonates the booster charge across an air gap approximately five times its diameter, an accomplishment not heretofore obtained in any fuse; and

Sixth. A fuse so designed that it operates satisfactorily in a shell loaded with high explosive—when an unavoidable air gap occurs due to loading or the set forward of the explosive in the shell when the latter strikes heavy armor.

What I claim is:

1. A percussion fuse comprising a fuse body in which is formed a chamber, a hammer block movable in the chamber and adapted to set forward on impact, and an anti-creeping coil spring at the rear of the plunger having its opposite ends attached respectively to the hammer block and the fuse body.

2. A percussion fuse, comprising a fuse body in which is formed a chamber, a hammer block supported in the chamber and free to move forward on impact, and an anti-creeping coil spring, the ends of the spring occupying recesses formed respectively in the hammer block and the fuse body, the inner walls of the recesses being screw-threaded and the spring being screwed into the said recesses and engaging with the threaded walls thereof.

3. In a percussion fuse, a hammer block, a firing pin carried thereby, pivotally supported so as to be free to oscillate, the pin being arranged to be moved to armed position by centrifugal force during the exterior flight of the shell carrying the fuse, and locking plunger pins for holding the firing pin in safety position, one movable radially and the other longitudinally of the fuse, the former being movable by centrifugal force to release the pin and the latter being movable and adapted to be "set back" to release the firing pin at the instant the gun is fired.

4. In a percussion fuse, a hammer block, a firing pin pivotally supported therein and arranged to normally occupy a safety position, the firing pin having an eccentric weighted portion, a radially acting locking pin for the firing pin, a longitudinally acting locking pin for the firing pin, the former being movable by centrifugal force to release the firing pin and the latter being arranged to be "set back" to release the firing pin when the gun is fired, the weighted portion of the firing pin being arranged to be acted upon both by centrifugal force and

by inertia, during the time the shell is accelerating during its flight, the arrangement being such that the force of inertia is greater than centrifugal force during the period of 65

5 the acceleration of the shell in the gun.

5. In a percussion fuse, a hammer block, a firing pin supported therein and arranged to normally occupy a safety position a longitudinally acting locking pin for the firing 10 pin, so arranged as to be set back to release the firing pin when the gun is fired, and means provided for preventing the said locking pin from engaging again with the firing pin until impact.

15. 6. In a high explosive detonating fuse, a plug carrying both a detonator and a delay powder train.

7. In a high explosive detonating fuse, a plug carrying a detonator and a plurality of 20 delay powder trains for igniting the detonator, the latter arranged to be ignited at separate points and to simultaneously burn out.

8. In a high explosive detonating fuse, a plug carrying a detonator, a delay powder train and a magazine of loose igniting powder between the powder train and the detonator.

9. In a high explosive detonating fuse, a plug carrying a detonator and a plurality of 30 delay powder trains arranged to be ignited at separate points and leading to a magazine of loose igniting powder adapted to fire the detonator.

35. 10. In a high explosive detonating fuse, the combination with the fuse body, of a single carrier plug separate from the fuse body, in which are located a time train and a detonator, a primer and means for firing 40 the primer, the primer igniting the time train and the latter firing the detonator.

45. 11. In a high explosive detonating fuse, the combination with the fuse body, of a single and separate carrier plug in which are located a plurality of time trains and a detonator, a primer, and means for firing the primer, the primer being arranged to ignite the several time trains and the latter being arranged to fire the detonator from a 50 common location.

55. 12. In a high explosive detonator fuse, the combination with a fuse body, a primer, and means for firing the primer of a detonator, a delay powder train arranged to be ignited by the primer, a magazine of igniting powder between said train and the detonator, and a single carrier, separate from the fuse body, in which are loaded the time train, magazine of igniting powder 60 and the detonator.

65. 13. In a high explosive detonating fuse, the combination with the fuse body and a primer and means for firing the primer, of a delay powder train arranged to be ignited

by the primer, a magazine of loose igniting powder to be fired by the time train, and a detonator to be fired by the magazine of igniting powder.

14. In a high explosive detonating fuse, the combination of a fuse body, a primer, a 70 plug carrying the primer having screw-thread connection with the fuse body, a separate plug arranged to be freely inserted into the fuse body and held in place in advance of the primer plug, and a detonator 75 carried by the said separate plug.

15. The combination stated in claim 14 including also a time train ignited by the primer and arranged to fire the detonator, carried by the said separate plug. 80

16. In a high explosive detonating fuse, a fuse body in which are formed chambers, one to receive a booster charge and the other to receive the primer and detonator, these chambers being separated by a partition 85 wall through which is a channel of communication, an automatically operating barrier in the said channel arranged to intercept the same when the fuse is unarmed, a plug for the primer having screw-thread 90 engagement with the fuse body, mechanism for firing the primer, and a carrier plug for the detonator and a time train adapted to freely move to its position against the said partition wall separating the chambers of 95 the fuse, such plug being held in place by the primer plug when the latter is screwed into position, and there being formed in the said carrier plug cavities adapted to receive respectively a time train ignited by the flash 100 from the primer and a detonator fired by the time train.

17. In a high explosive detonating fuse, a fuse body in which are formed chambers, one to receive the booster charge and the 105 other to receive the primer and detonator, these chambers being separated by a partition wall through which is a channel of communication, an automatically operating barrier in the said channel arranged to intercept 110 the same when the fuse is unarmed, a plug for the primer having screw-thread engagement with the fuse body, mechanism for firing the primer, and a plug carrying a 115 detonator and delay powder trains, the carrier plug being adapted to freely move to its position against the partition wall separating the chambers of the fuse, and being held in place by the primer plug when the latter is screwed into position, the detonator and delay powder trains occupying, respectively, cavities in the carrier plug, and the powder trains being arranged to be simultaneously ignited by the flash from 120

125 the primer and to simultaneously burn out and deliver their flames in a common locality to ignite the detonator.

18. The combination stated in claim 17 in-

cluding also a magazine of igniting powder arranged between the ends of the delay powder trains and the detonator.

19. In a high explosive detonating fuse, the combination with a fuse body, a primer, means for firing the primer, a carrier for a detonator and powder time trains, formed of a plug of metal freely movable to position within the fuse and having formed in 10 one end a cavity to receive the detonator and in its other end channels to receive the time trains, the cavity and channels communicating, and the channels for the time trains opening into a flash passage leading from 15 the primer, and means for securely holding in position within the fuse the said carrier plug.

20. In a percussion fuse, a chambered fuse body, a plug carrying a primer having 20 screw-thread connection with the wall of the fuse chamber, mechanism for firing the primer located within the said chamber, a carrier plug for a time train also located in the chamber, and a disk of yielding nature 25 interposed between the primer plug and the said carrier for the time train arranged to operate as a seal for the time train except the end thereof which is intended to be ignited by the flash from the primer.

21. In a high explosive detonating fuse, a chambered fuse body, a plug carrying a primer having screw-thread connection with the wall of the fuse chamber, mechanism for firing the primer located within the said 30 chamber, a carrier plug for both a detonator and time trains, freely movable within the chamber and arranged to be held securely in place by the primer plug, and a disk of yielding nature interposed between the 35 primer plug and the carrier plug and arranged to operate as a seal for the time trains, except the ends thereof which it is intended should be ignited by the flash from the primer.

22. In a high explosive detonating fuse, a carrier plug having formed in one end a cavity for a detonator, having an interior cavity for a magazine of igniting powder communicating with the detonating cavity, 40 having a channel for a delay powder train communicating with the cavity for the magazine of igniting powder, and having an opening through which the loose igniting powder may be loaded into its cavity, 45 and a tightly fitting plug for closing the said opening.

23. In a high explosive detonating fuse, a carrier plug having formed in one end a cavity for a detonator, having a central interior cavity for a magazine of igniting powder, having a plurality of channels for 50 delay powder trains leading from the said central cavity to the periphery of the plug, and having an opening through the end of

the plug opposite that in which is formed 65 the detonator cavity through which the interior central cavity may be loaded with igniting powder, and a tightly fitting plug for closing the said opening.

24. A fuse formed with a threaded channel into which is loaded and compressed a 70 delay powder train.

25. A fuse, provided with two primers arranged in series, and means for successively firing the said primers.

26. A fuse having a single firing pin arranged to function on impact and two primers arranged in series, both adapted to be ignited by the firing pin, the primer nearest the firing pin being of the stab type, and 80 the other of the percussion type.

27. In a detonating fuse, the combination of a rigid carrier having an open ended cavity, the wall of which flares toward the 85 front and converges toward the rear, a detonating charge loaded in the said cavity, a charge of high explosive a channel of detonation between the detonator and the charge of high explosive, and means for firing the detonating charge, the recited features being so arranged that on firing the detonating charge the resulting waves of detonating force are reflected from the wall of the cavity in which it is located, and directed forwardly and through the said 90 channel of detonation, and caused to directly act upon and detonate the high explosive charge.

28. In a detonating fuse, the combination of a rigid carrier having a cavity flaring 100 outward towards the front and converging to and closed at the rear except for a firing passage, a detonating charge loaded in said cavity, a charge of high explosive, and a channel free from explosive, of greater 105 length than its width, between the said detonating and high explosive charges, so that on the firing of the detonating charge, the resulting waves of detonating force reflected from the wall of the said cavity pass 110 through the said open channel and effectively detonate the said high explosive charge.

29. In a detonating fuse, the combination of a rigid carrier having a cavity flaring 115 outward towards the front and converging to and closed at the rear, a detonating charge loaded in said cavity, an open channel free from explosive, of greater length than its width, communicating with said detonating 120 charge, and means for firing the said charge, so that on its explosion the resulting waves of detonating force are reflected from the wall of said cavity and pass through the said open channel.

30. In a detonating fuse, the combination of a rigid carrier having a cavity flaring 125 outward towards the front and converging

to and closed at the rear except for a firing passage, a detonating charge loaded in said cavity, and a channel free from explosive of greater length than its width communicating with said detonating charge, through which the waves of detonating force are transmitted on the explosion of the said detonating charge.

31. In a detonating fuse, the combination 10 of a rigid carrier having a cavity flaring outward towards the front and converging to and closed at the rear, a detonating charge loaded in said cavity, an open channel free from explosive and also contracted as compared with the width of the said cavity and 15 communicating with said detonating charge, and means for firing the latter so that on its explosion the waves of detonating force are reflected through said open and contracted 20 channel.

32. In a detonating fuse, the combination of a rigid carrier having an open ended cavity of substantially parabolic curvature, a detonator loaded in said cavity, a firing 25 passage at the rear thereof, so that on the explosion of the detonator the resulting waves of detonating force are reflected from the wall of said cavity and pass out through the open end thereof and a shield closing 30 the opening of the said firing passage into the detonator cavity.

33. In a detonating fuse, the combination of a rigid carrier having an open ended cavity of substantially parabolic curvature, a detonating charge loaded in said cavity, a 35 metal shield, thicker at the middle than at the edges, closing the open end of said cavity, and means for firing the said detonating charge, so that the waves of detonating force will be reflected from the wall of the said cavity and pass through and be refracted as desired by the said shield.

34. In a detonating fuse, the combination 45 of a booster charge, a detonator exterior thereto and loaded in a cavity the rigid wall of which reflects and directs the waves of detonating force resulting from the explosion of said detonator so that they will act effectively across a considerable air gap, 50 means for firing the detonator, a channel of detonation free from explosive connecting said booster charge and detonator, a barrier intercepting said channel when the fuse is in safety position and capable of being automatically moved into armed position making the channel of detonation continuous, so 55 that on the explosion of the detonator the resulting waves of detonating force pass through the length of the said channel and detonate the booster charge.

35. In a fuse, a highly compressed detonator loaded in a cavity the interior of which flares outward to the front and converges to the rear, the wall enclosing the 60 cavity being thick and rigid, the rear of the

cavity having an igniting passage for effectively exploding the detonator in said cavity.

36. In a fuse, a separable carrier for a detonator in which is formed a cavity flaring toward the front and converging toward the rear and with an ignition opening in its rear portion, the wall of the carrier surrounding the cavity being thick and rigid, a charge of a highly compressed detonator in the said cavity, and means for firing the detonator at the said ignition opening. 70

37. In a detonating fuse, a fuse stock having a chamber for the booster charge, a second chamber for an intercepting barrier, and a third chamber for the firing mechanism, and primer elements, all said chambers being so designed and arranged that the booster charge is loaded from the front, 80 the barrier assembled from the side, and the firing mechanism, primer and detonating elements assembled from the rear, and each independently of the others. 85

38. In a detonating fuse, the combination 90 of a fuse stock having a channel of detonation, a barrier adapted to intercept such channel, an expansion chamber in proximity to the barrier, and a detonator at the rear end of the channel of detonation, all so 95 designed and arranged that in the event of the premature explosion of the detonator, the barrier would be deformed, permitting the resulting explosive gases to be diverted into the expansion chamber. 100

39. In a detonating fuse, the combination of a fuse stock having a channel of detonation, a barrier adapted to register with and to intercept said channel, an expansion 105 chamber in proximity to the barrier, the channel of detonation being exposed to the exterior through an opening in the fuse stock, and a screw plug for closing said opening, and all so designed and arranged that on removing the said screw plug the position of the barrier with reference to the channel of detonation may be observed and inspected. 110

40. In a detonating fuse, a fuse stock formed with chambers in one of which is a booster charge and in the other a detonator, there being a channel of detonation between such chambers, a movable barrier arranged to intercept the said channel when in one position and to open it when in another, there being formed in the fuse stock an expansion chamber open to the exterior and in proximity to the barrier, to receive the explosive gases should the detonator prematurely explode, when the channel of detonation is closed by the barrier, the opening to such chamber being located to permit inspection of the barrier from the outside, and a plug for closing the opening. 115 120 125

41. In a detonating fuse, the combination 130

of a booster charge, a detonator exterior thereto and loaded in a cavity the rigid wall of which directs the waves of detonating force resulting from the explosion of said detonator so that they will act effectively across a considerable air gap, means for firing the detonator, a channel of detonation free from explosive connecting said booster charge and detonator, a barrier intercepting said channel when the fuse is in safety position and capable of being automatically moved into armed position, so that on the explosion of the detonator the resulting waves of detonating force pass through the length of the said channel and detonate the booster charge.

42. In a detonating fuse, the combination of a detonator loaded into a cavity the rigid wall of which reflects and concentrates the waves of detonating force resulting from the explosion of said detonator so that they will act effectively across a considerable air gap, means for firing the detonator, a chan-

nel of detonation free from explosive leading from the said detonator, and a barrier intercepting the said channel when the fuse is in safety position and capable of being automatically moved into armed position, making the channel of detonation continuous, so that on the explosion of the detonator the resulting waves of detonating force pass through the entire length of the said channel.

43. In a detonating fuse, the combination of a booster charge, and a detonator exterior thereto, a channel of detonation, free from explosive, connecting said booster charge and detonator, a movable barrier intercepting the said channel when the fuse is in safety position and capable of being moved automatically to arm the fuse, making the channel of detonation continuous, so that on the explosion of the detonator the resulting waves of detonating force pass through the entire length of the said detonating channel and detonate the booster.

CHARLES P. WATSON.
